UNITED STATES PATENT OFFICE.

WALTER H. BARBER, OF STONEHAM, MASSACHUSETTS, ASSIGNOR TO SUBMARINE SIGNAL COMPANY, OF PORTLAND, MAINE, A CORPORATION OF MAINE.

HYDROPHONE.

Application filed May 25, 1921. Serial No. 472,538.

I have made a new and useful improvement in apparatus suitable for detecting under-water sounds. Heretofore microphones have been used as a portion of submarine signaling apparatus to detect the sounds which are created when bells are struck under water or when a series of undamped sound waves are produced under water by such a device as an oscillator. 5 Such microphones were, in general, designed to be most responsive to notes of the frequency of the signaling source and efforts were made to arrange the microphone and its mounting in such a way that 10 it was responsive only to sounds of the frequency of the signaling source.

The microphone or hydrophone which I have invented has for its object, not merely the detection of a sound of definite or sustained pitch, but also the detection of all sounds, so that the hydrophone will give immediate indication of ships, whether visible or invisible, or other moving vessel such as a submarine as well as of musical 20 or bell noises. As there may be more than one vessel creating submarine noises within the range of the hydrophone, it is of fundamental importance that a hydrophone to have the greatest usefulness should reproduce the characteristics of the sounds 25 created by each source of sound waves. In other words, the hydrophone as a whole must be as nearly as possible free from any characteristics of its own, or must be what 30 may be called aperiodic. As these hydrophones will be used in most cases with compensators for the ascertainment of the direction and position of the invisible sound source, the two or three hydrophones used 35 in conjunction for this purpose must be similar in volume and have as nearly as 40 may be possible the same characteristics.

My invention consists of a new form of current-varying element, or as it will be 45 called "microphone button" or "button" for use in hydrophones designed especially for uses as submarine sound detectors and with direction-finding devices.

A button for a hydrophone used to detect ship's noises must be equally sensitive 50 at all times even to sounds of the smallest intensity; and must be so made as to have the least possible natural pitch of its own. The first of these requirements I have obtained by so designing the carbon chamber

and by using such amounts of carbon as will allow just the right amount of current to pass at all times and will never admit a rise in current strength sufficient to overheat the button and thus produce "packing," that is, 60 a short-circuiting of the button through something analogous to the "coherer" action which is well known in detectors for wireless signals. I have accomplished this 65 by using a washer of highly elastic insulating material. This washer is held between the two electrodes which form the front and back of the carbon chamber. Holes are made through this washer of a size and shape such that the necessary amount of 70 carbon will be contained in the pockets thus formed, and the washer is so placed in the button and the button is so mounted in the hydrophone case that there is never too great a pressure, arising from gravity, of 75 the carbon within a pocket. It is known that felt or velour washers have been used in microphones and that holes have been punched in these washers to form chambers 80 for the reception of the granular carbon, but the form and size of these chambers have failed to give the extraordinary results, both in uniformity and sensitiveness, which I have obtained in my button when 85 used as a noise-detecting hydrophone.

I have likewise obtained unusual sensitiveness in my button by the shape which has been given to the front electrode. As stated above, it is of fundamental importance to have the button of the requisite 90 resistance and this can be obtained only by having a fairly large electrode surface as well as a proper amount of granular carbon between the electrode surfaces. It is also important to keep the weight of the button as 95 light as may be reasonably possible and, as a consequence, the size of the complete button must be kept small. The sensitiveness of the button can be increased by increasing the free or unclamped area of the elastic 100 disk or washer, which supports the front electrode, and by means of which the front electrode is held mechanically upon the case of the button. I have obtained this necessary sensitiveness preferably by undercutting or chamfering the piece to which the front electrode is attached so as to retain a full-sized front electrode and, at the same time, obtain a greater freedom of the elastic 105 member which supports the button than has 110

hitherto been found possible with the small sized button which I employ.

Still another feature of my button which has been discovered after years of trial (the physical significance of which I have been unable to explain satisfactorily) is the use of two elastic members similar in all respects, clamped together so as to operate virtually as a single elastic member. Hitherto

10 the elastic member has been a single disk or plate of mica or other elastic material, or two or more elastic disks separated from each other. I have found that by the use of two elastic members clamped together, as if

15 they were a single member, I can obtain a more characteristic reproduction of the original source of sound with greater freedom from individual characteristic tones and at the same time with increased rather than decreased sensitiveness to feeble sounds from the source.

My invention will be understood by reference to the drawing in which it is shown in its preferred form.

25 Figure 1 shows a side elevation of the hydrophone, the view being partly in section to show the mounting of the button.

30 Fig. 2 is a sectional view of all the parts of the button except the frame which is in elevation, the parts being shown in unassembled relation.

35 Fig. 3 is a plan of the elastic washer, and Fig. 4 is a section showing the assembly of the parts.

40 Fig. 5 shows in vertical section a form of mounting useful where the hydrophone is used in a tank on board ship.

Fig. 6 is a side elevation thereof.

45 Fig. 7 is a front view of a support by which the hydrophone may be arranged to hang in substantially horizontal position.

Fig. 8 shows the same support in closed or gripping position.

45 Fig. 9 is a section on line 9—9 of Fig. 7, and

Fig. 10 is a reduced fragmentary section of the tank with the hydrophone supported therein.

50 1 is a metal containing case or cup in the bottom of which is soldered by solder 100 the back electrode 2. I have used highly polished carbon for the active face of this back electrode, but a highly polished surface of metal which does not oxidize may equally well be employed. A washer 3 of felt or any other elastic non-conducting material is inserted in the cup and fills with the least possible compression the space between the back electrode 2 and front electrode 6. The washer 3 is shown as having slots 4 and 5 which when the washer is in place between 2 and 6 form two cavities in which the granular carbon is placed. A plan view of washer 3 is shown in Fig. 3. An important feature of this washer is the general shape of the

55 cavities or chambers which provides for a considerable bulk of carbon which may be extended laterally across the greater portion of the diameter of the washer in comparatively thin layers so that the packing effect 70 of gravity is negligible, and at the same time sufficient granular carbon may be used to secure good results. When assembled in the button the washer 3 is so placed that the slots have their greatest dimensions horizontally. The active front surface of electrode 6 may be made as large as possible so as to cover slots 4 and 5 in washer 3 and thus prevent the granular carbon from falling or working its way out from the cavities. This front electrode 6 has a highly polished surface where it bears upon the granular carbon. Electrode 6 has been made of carbon in the buttons which I have manufactured, but any conductor which can be highly polished and will not corrode may be used. As shown, the front electrode 6 is soldered to metal piece 7 the front face of which is thinned near its edge to allow the disks 10 and 13 to have considerable play near their edges, their central clamped area thus being considerably less than the active area of the electrode 6.

60 Piece 7 has a smooth shank at 8 for a distance a little less than the thickness of clamping washer 14, and has the remainder of the shank threaded at 9. 10 and 13 are two similar disks of elastic insulating material forming together a laminated diaphragm. I have found mica well suited for the purpose. Holes 11 and 12 in disks 10 and 13, respectively, permit these disks to be passed over shank 8. The clamping washer 14 has the same outside diameter as the thicker part of the piece 7 and has a hole 15 through it of a diameter such that it can just pass onto shank 8 of brass piece 7. Clamping nut 16 has a threaded hole 17 which permits it to be screwed onto the screw thread 9 of brass piece 7. Thus when this portion of the button is assembled the two mica washers are firmly clamped at their middle between brass piece 7 and nut 14 and at their edges by the crimping ring 18, the points on the clamped discs 10 and 13 comprising the diaphragm between the crimping ring 18 and the clamping nut 16, being free to move so that an unusual amount of vibration is given to the diaphragm by the electrode, the portion of the diaphragm which is free to move being of smaller internal diameter than the diameter of the electrode. It will be understood that the electrode and its support may be integral if desired. I have adopted this mechanical construction and used clamping nut 16, rather than threading washer 14, and using it for the clamping nut, for the reason that I have found by very careful experiment 110 that, if washer 14 is turned against the sur-

face of disk 13 during the assembly of the button, as would have to be done if 14 were threaded and used as a clamping nut, the surface of the elastic disk 13 would be 5 cut or scratched sufficiently to seriously affect the operating efficiency of the button. 18 is the crimping ring which is passed over the cup 1. When the entire button above described has been assembled with the requisite 10 carbon in pockets 4 and 5, it is placed in a press and the crimping ring 18 is forced upon the cup 1 under great pressure by means of a device well known. The flange 19 of the crimping ring is turned about the flange 15 20 of the cup, thus firmly binding the elastic disks 10 and 13 between the crimping ring and the top surface of the rim 20 of cup 1 and thus retaining the elastic disks firmly bound between the crimping ring and the 20 cup and consequently holding all other portions of the button in their proper positions. Thus the vibratory area of the button is large in proportion to the diameter of the button and is capable of greater freedom and amplitude of vibration than is 25 usual in other buttons of the same size.

In order to make connection with the button without in any way restricting the freedom of movement of the button, I prefer 30 to use a light metal rectangular frame 21. This frame is large enough to surround the button and has a hole 22 through one side to receive the end of screw 9 which passes through it and is held by nut 26. At the 35 opposite side are two pins 23 and 24 one of which 23 is insulated from the frame by suitable bushings 25. The frame and pin 24 thus form the connection with the front electrode and a flexible wire soldered to cup 40 1 and to pin 23 forms the connection with the back electrode.

Fig. 1 shows a button such as has been described above mounted in a form of hydrophone made in two parts 27, 28, which has 45 been extensively used in the detection of noises produced by distant ships. The case of this hydrophone is reasonably aperiodic, being made of rubber and in two parts 27, 28. Within is a sleeve 29 grooved as at 50 30 to receive the outer rubber casing which fills these grooves, the sleeve thus holding these parts together. Within this sleeve is a core 31 which acts as a stuffing box and carries the connecting wires and terminals 55 32 to which the leads from pins 23 and 24 are connected. The frame 21 is attached to the interior of the casing member 27 by the screw 9 which screws into a socket in a metal piece 33 moulded in the casing member 27. 60 34 is a clamping ring to clamp the rubber tightly against the sleeve 29. It may be used to hang the hydrophone to a suitable float.

In the form of my invention shown in 65 Fig. 5 the button is supported in a rubber casing one portion of which is marked 27.

The part 27 carries a metal piece 33 to which the button is attached by the screw 9 as before. A flanged metal sleeve 35 forms the side walls of the chamber within the hydrophone and around this sleeve lies a sleeve 70 36 projecting from the other member 37 of the hydrophone casing, which carries preferably a lead disk 39 forming one of the ends of the chamber.

The leads from the terminals 32 are enclosed in a cable 40 which passes up through a tube 41 forming part of the member 37 and preferably the cable is cemented to the interior of the tube or otherwise attached thereto to prevent leakage. Around the hydrophone approximately midway between its two ends, is a strap 341 having a piece 42 which projects upwardly and carries a yoke 43. The strap 341 is open at one side and provided with a hook member 342 adapted 85 to catch over the shoulder 343 on the other end of the strap so that, as shown in Fig. 8, where the strap is placed about the hydrophone, these two ends of the strap will overlap and the hook 342 catch onto the shoulder 343 and the two may then be fastened by the screw 344, as shown in Fig. 6. The tube 41 is then passed up into the yoke 43 and the ends of the yoke are bent around as shown in dotted lines in Fig. 9 so 90 that when suspended by the tube 41 the hydrophone will hang substantially in a horizontal position, this position being assisted by the weight of the disk 39 which balances the weight of the flange of sleeve 35. 100

In Fig. 10, 44 indicates a tank on board ship which is filled with water and in which the hydrophone is submerged. The tube 41 is sufficiently long to pass out through the top of the tank 44, a stuffing box being used 105 if desired so that the water is never in contact with the leads.

I have described above an instrument which has shown itself to be an improvement over microphones heretofore used as 110 sound receivers in the submarine art and so far as I know it is the best embodiment of my invention now known to me, but I do not mean to limit myself to the precise construction shown. Its practical advantages seem to result from the use of a laminated member or diaphragm to pick up the sound waves (this laminated member being substantially aperiodic) and the means described for containing the carbon granules whereby there is secured a minimum tendency for the granules to pack. This device has been thoroughly tested and has proved 115 itself particularly efficient in use. 120

What I claim as my invention is:—

1. A microphone button comprising two electrodes and a diaphragm comprising separate and independent disks of elastic material of the same diameter in contact and clamped together at their edges to form a 130

single vibratable member, said disks having the same coefficient of expansion, one of said electrodes being connected to said diaphragm to move therewith.

5 2. A microphone button comprising an electrode support having an electrode attached thereto, said support having an edge

thinner than its central portion, and a diaphragm clamped to and in contact with said central portion only and extending beyond the thinner edge of said support whereby its vibrations will not be damped thereby.

WALTER H. BARBER.
